UNITED STATES PATENT OFFICE

1,993,293

MACHINE FOR REDUCING HEEL-BREAST
COVERING FLAPSLewis J. Bazzoni, Swampscott, Mass., assignor to
United Shoe Machinery Corporation, Paterson,
N. J., a corporation of New Jersey

Application February 7, 1933, Serial No. 655,629

28 Claims. (Cl. 51—145)

This invention relates to machines for use in the manufacture of shoes and is illustrated as embodied in a machine for abrading heel-breast covering flaps.

5 In United States Letters Patent No. 1,983,591, granted December 11, 1934 on an application filed in my name there is disclosed a machine which may be operated effectively to reduce the heel-breast covering flaps of attached or unattached soles of shoes at selected localities preparatory to cementing the flaps to the breasts of heels.

10 It is an object of the present invention to provide an improved machine which may be used rapidly and effectively to reduce the heel-breast covering flaps of soles of shoes with a minimum amount of effort on the part of the operator.

15 With the above object in view, and in accordance with a feature of the invention, each of the illustrated machines includes a pair of supports which are constructed and arranged for engagement with the shank and heel-seat portions respectively, of a sole having a heel-breast covering flap split therefrom and are spaced to provide an opening through which the flap extends, a 20 matrix plate, an abrasive member, and means for effecting relative movement of the abrasive member on one hand and the matrix plate and the supports on the other hand in an orbital path to reduce the flap at selected localities.

25 Each of the illustrated machines is provided with a plurality of units, each of which comprises a matrix plate and mechanism for supporting and positioning the sole, and a turret upon which the units are mounted in order successively to move the same past a sole-loading station and then past the abrasive member. The support for the heel-seat portion of the sole is provided with an undercut face which deflects the flap into the opening formed between the supports as the sole 30 is moved rearwardly, flesh side up, between a pair of centralizing rolls and against the heel-seat engaging support. The matrix plate of each of the units may be mounted for adjustment relatively to the support for the shank portion of the sole in order to vary the distance between the opening and the matrix plate and thereby to vary, when desirable, the distance between the base of the flap and the flap portion to be reduced.

35 Fig. 1 is a side elevational view of an illustrated machine for abrading heel-breast covering flaps;

40 Fig. 2 shows a plan view of the machine illustrated in Fig. 1;

45 Fig. 3 is a sectional view taken along line III—III of Fig. 2;

5 Fig. 4 is a sectional view taken along line IV—IV of Fig. 3;

Fig. 5 is a detail view showing mechanism for supporting and adjusting a lower pulley which carries the rotary abrasive belt of the machine illustrated in Figs. 1 to 4;

10 Fig. 6 is a side elevational view of a modified machine for abrading heel-breast covering flaps;

Fig. 7 shows a vertical section of the machine 15 illustrated in Fig. 6;

Fig. 8 is an enlarged view of one of the sole-supporting and positioning units of the machine 20 illustrated in Figs. 6 and 7;

Fig. 9 shows in section a suction-pipe for disposing of leather-dust, the section being taken 25 along line IX—IX of Fig. 3; and

Fig. 10 is a perspective view of the rear part of a sole, the heel-breast covering flap of which has been reduced by the above-illustrated machine.

20 One of the illustrated machines is provided with a rotary table 20 (Figs. 1 to 4) comprising sole-supporting and positioning units, each of which includes plates 22, 24 (Figs. 3 and 4) constructed and arranged to support the shank and heel-seat portions 26, 28 (Fig. 10), respectively of a sole 29 25 having a heel-breast covering flap 30 split therefrom. The plates 22 are illustrated as comprising parts of the table 20. The plates 24 are preferably formed of pieces separate from the table 30 and have sole-engaging faces 32 spaced from the sole-engaging faces 34 of the plates 22 to form openings or slits 36. The heel-breast covering flap 30 of the sole supported and positioned upon the plates 22, 24 extends through and beyond the opening 36 preparatory to rotating the table 20 35 past an abrasive member or belt 38 (Figs. 1 and 2), for forcing the portion of the flap projecting through the opening 36 against a matrix plate 40 which is positioned beneath and clamped to the under-side of the plate 22 by screws 41, thereby to reduce the thickness of the flap 30 at selected localities for producing a flap such as illustrated in Fig. 10.

40 It is sometimes the practice to retain the full thickness of the heel-breast covering flap 30 at the central part 42 of its base and to skive the flap lengthwise and widthwise from such part to form a V-shaped reinforcement 44. The margin 46 of the flap 30 may be trimmed to uniform but reduced thickness and after the flap has been 45 cemented to the breast of the heel it is trimmed to the outline of the breast of the heel.

50 Although the illustrated machines are described with reference to the forming of the V-shaped reinforcement 44 and the flap-margin 46 of re- 55

duced thickness, it will be understood that matrix plates of various sizes and shapes may be used in accordance with the shape of the heel-breast covering flap.

5 The rotary table 20, which may also be referred to as a turret, is of circular form and is provided with a hub portion 45 mounted for rotation upon an upstanding post 47 carried by a standard 48. The table 20 may be supported for rotation upon the standard 48 by an anti-friction bearing (not shown). The turret or table 20 is rotated upon the upstanding post 47 through a worm 50 (Fig. 2) which meshes with a circular rack 52 formed at the lower part of a depending flange 54 of the table 20. The worm 50 is driven by a pulley 56 which is connected through a belt 58 to a pulley 60 keyed to a shaft of an electric motor 62.

When it is desired to provide a heel-breast covering flap having a reinforcement extending substantially the entire length of the flap, it has been found preferable to place the sole in sole-supporting and positioning units which are mounted upon a rotary drum 63 (Figs. 6 and 7) and will be referred to later. The rotary drum 63 may be referred to as a turret and is mounted upon a bearing shaft 66 supported by a standard 68, the drum being rotated by a worm 70 constructed and arranged to mesh with a circular rack 72 formed integral with the drum.

30 The illustrated abrasive belt 38 (Figs. 1 and 5) is carried upon upper and lower pulleys 74, 76 mounted upon shafts 78, 80, respectively, which are rotatably secured in bearing blocks 82, 84, respectively. The shaft 78 carries a pulley 86 which is connected to a drive pulley 88 secured to the shaft of the electric motor 62 by a belt 90.

In order to adjust the abrasive belt 38 toward and away from the path of movement of the matrix plates 40 according to the desired thickness of the margin 46 of the reduced flap, the upper bearing block 82 is formed integral with a dovetail slide 92 (Fig. 1) constructed and arranged for adjustment along a slideway 94 of the main frame. This adjustment may be effected after releasing set screws 96 by turning a rod 98, the lower end of which rests on a stud 100 and the upper end of which is in threaded engagement with a collar 102 mounted upon a pin 104 secured to a flange of the bearing block 82. After the bearing block 82 has been adjusted heightwise, it is clamped to the main frame by the set screws 96.

55 The lower bearing block 84 is pivotally mounted upon a pin 106 carried by a slide 108 which is provided with an internally threaded lug 110 arranged to receive a threaded portion of the stud 100 which is rotatably secured to a boss 112 of the frame of the machine. In order to adjust the pulley 76 about the pin 106 to set the same for proper engagement with the abrasive belt 38, the bearing 84 is provided with an extension 114 (Fig. 5) having a threaded recess for receiving an adjusting screw 116, the end of which engages the slide 108. A lock nut 118 is used to clamp the screw 116 to the extension 114.

In order to lock the slide 108 and to release the same for adjustment along the slideway 94, the illustrated machine is provided with a pair of set screws 122 in threaded relation with the main frame and having their respective ends in engagement with a gib 124. The rod 98 is hinged through the collar 102 with respect to the upper bearing block 82 in order to facilitate the lowering of the pulley 74 below the depending flange 54 of the table 20 when placing a new abrasive belt 38 upon

the pulleys 74, 76. By mounting the abrasive belt 38 as above described, such belt may be properly tensioned without affecting the adjustment of the upper pulley 74 with respect to the path of movement of the matrix plates 40.

5 An abrasive belt 127 included in the embodiment illustrated in Figs. 6 and 7 is mounted upon upper and lower pulleys 128, 130 which are carried upon upper and lower blocks 132, 134, respectively. The upper block 132 has an extension 136 shaped and arranged for adjustment along a slideway 138 of a stationary bracket 140 which is bolted to the main frame. The block 134 is pivotally connected to a slide 142 which is mounted for adjustment along the slideway 138. In order initially to align the abrasive belt 39, the pulley 130 may be angularly adjusted relatively to the slide 142 by turning a rod 144 which is in threaded relation with the slide 142 and has an abutment 146 arranged to engage a depending arm 148 of the block 134. The arm 148 is urged toward the abutment 146 by a spring 150 carried by the rod 144 and having its opposite ends in engagement with the slide 142 and the arm 148, respectively. The slides 136 and 142, after being adjusted heightwise of the slideway 138, by turning an adjusting rod 152, are clamped to the bracket 140 by screws 154, 156, respectively.

20 The soles are successively placed flesh-side up upon the table 20 as the sole-supporting units 30 arrive at a sole-loading station A (Figs. 2 and 6). To facilitate the positioning of the sole in the machine illustrated in Figs. 1 to 5, inclusive, each unit is provided with a pair of centralizing arms 158 which carry rolls 160 arranged to extend into 35 the opening or slit 36 and mounted for equal and opposite movement about screws 162 with respect to the supporting plates 22 and 24. As the operator moves the sole, heel-end first, between the rolls 160, the flap engages the plate 24 which is 40 provided with an undercut face 164 constructed and arranged to engage the flap as the sole is pushed rearwardly, and to guide or deflect the same through the opening or slit 36.

45 The throat formed between the centralizing rolls 160 is of sufficient width to accommodate the smallest sole being operated upon and may be varied in width by turning the thumb nut 166. A spring 168 which normally urges the arms 158 into a closed position is of suitable strength to 50 permit the operator by slightly forcing the rear end of the sole against the rolls 160 to spread the arms 168 apart.

55 The length of the flap 30 to be formed varies in accordance with the size of the sole being split, and the V-shaped reinforcement 44 is usually formed at a constant distance from the forward end 170 (Fig. 10) of the flap in soles of different sizes and shapes.

As the flap 30, after being positioned widthwise at the sole-loading station A, is rotated with the table 20, it comes into contact with a flap-guide or plow 172 which is positioned immediately in front of the top of the abrasive belt 38 and is shaped and arranged to move the flap into a 65 position adjacent to the matrix plate 40 preparatory to forcing the flap against the same.

70 When the abrasive belt 38 engages the flap 30 it drags the same relatively to the table 20 until the forward end 170 of the flap is positioned 70 adjacent to one end of the opening, as illustrated in Fig. 3, and then forces the flap against the matrix plate 40 to remove material from the same at selected localities. It will thus be noted that it is only necessary for the operator to place 75

the sole of the shoe upon the plates 22, 24 in such a position that the flap extends a substantial distance through the opening 36, since the abrasive belt before reducing the flap, positions the sole lengthwise and also orients the same with respect to the rolls 160.

The slit or opening 36 should be of sufficient width to permit the flap 30 quickly to be inserted through the slit but should not be so wide that the portion of the sole that bridges the opening is flexed due to the pull of the flap during the abrading operation. In order to vary the width of the opening, the plate 24, which may be referred to as a separator plate, is adjustably mounted upon the table 20 through a pair of screws 174 (Fig. 3) which are in threaded relation with the plate 24 and pass through slots 176 respectively formed in the table 20.

It is sometimes customary to split the sole a considerable distance forwardly of its breast line 180 in order to form a flap of sufficient length to enable the operator to bevel the forward edge of the projecting lip of a Louis heel, which is to be attached to the shoe, with a rasp, thereby to insure that the lip of the heel of the finished shoe will merge smoothly with the shank portion of the sole. In order accurately to position the V-shaped reinforcement 44 in soles, the heel-breast covering flaps of which are split different distances forwardly of the heel breast line 180, the matrix plates 40 may be initially adjusted relatively to their corresponding openings 36. Such adjustment is effected by loosening the screws 41, which are in threaded relation with the matrix plate 40 and pass through slots 182 formed in the table 20, and by then moving the matrix plate 40 along a recess 184 (Fig. 4) formed in the under-side of the table 20 until the matrix plate 40 engages a curved edge 186 of an abutment plate 188 (Fig. 3). Secured to the stem of the abutment plate 188 is an indicator finger 190 which may be turned initially to adjust the plate 186 in accordance with the distance to which the flap 30 has been split forwardly of the heel breast line 180. In order to assist the operator in adjusting the abutment plate 188, the top of the table 20 is provided with a scale 192 (Fig. 2) for setting the indicator finger 190. When the matrix plate 40 has been moved into engagement with the abutment plate 188, the screws 41 are again tightened to clamp the matrix plate 40 in adjusted position to the table 20.

It is desirable to dispose of leather-dust which has been removed from the heel-breast covering flap and, accordingly, the machine is provided with a suction pipe 194 having its throat positioned immediately in rear of the upper part of the abrasive belt 38 (Figs. 1 and 3). The top of the suction pipe adjacent to the abrasive roll 60 may be formed by the flap-guide 172 which, as stated, bends the flap toward the matrix plate 40 as the table is rotated. Suction is induced in the pipe 194 by a fan 196 which is driven from the motor 162 through a belt 198.

In order to reduce the heel-breast covering flap 30 at selected localities, the operator, after initially adjusting the machine, successively places soles flesh side up in the units carried by the table 20 as they arrive at loading-position A, and pushes the heel-seat portion of the sole between the rolls 160 to centralize the sole. In the meantime, the heel-breast covering flap strikes the undercut face 164 of the plate 24 which projects slightly above the table 20, to force the flap through the slit or opening 36 so that the major

portion of the same extends below the lower face of the table 20. As the table 20 rotates, the flap-guide 172 bends the portion of the flap extending below the table 20 toward the matrix plate 40 and as the flap moves past the upper part of the rotary abrasive belt 38 (Figs. 1 and 3) it is forced against the matrix plate 40 and is reduced at selected localities. When the skiving operation has been performed the operator removes the sole from the unit or, if desirable, the machine may be equipped with mechanism for automatically ejecting the work from the machine.

Since the sole-supporting and positioning units carried by the drum 63 illustrated in Figs. 6, 7 and 8 are identical with corresponding units illustrated in Figs. 1 to 5, except for certain parts which are slightly curved in accordance with the curvature of the drum 63, it will not be necessary to describe the construction and the operation of such units in detail. Accordingly, the parts of the sole-supporting and positioning units of the modified machine of Figs. 6, 7 and 8 which are substantially identical with the corresponding parts of the machine of Figs. 1 to 5 have been given respectively the same numerals each with the exponent a.

Having described my invention, what I claim as new and desire to secure by Letters Patent of the United States is:

1. An abrading machine having, in combination, a support for a sole having a flap split therefrom, said support being provided with a slit to receive said flap, a matrix, an abrasive member, and means to move the support and the matrix past the abrasive member thereby to cause the flap to be forced against the matrix by said member for varying the thickness of the flap at selected localities.

2. A machine of the class described having, in combination, a table to support a sole having a flap split therefrom and provided with a slit to receive the flap, a matrix secured to the underside of the table, and a flap-reducing member, said table being mounted for rotation to carry the matrix in an orbital path and past the flap-reducing member thereby to cause the flap to be forced against the matrix for skiving the same to a shape determined by the matrix.

3. A machine of the class described having, in combination, supports constructed and arranged to engage the heel seat and the shank portions respectively of a sole having a heel-breast covering flap split therefrom and spaced from each other to provide an opening through which the flap extends when the sole is in engagement with said supports, a matrix plate adjustably secured to one of the supports, a flap-reducing member, and means to move the supports and the matrix plate past the flap-reducing member to cause said member to force the flap against the matrix plate thereby to skive the flap at selected localities.

4. An abrading machine having, in combination, supports provided with faces which are constructed and arranged to engage the heel seat and the shank portions respectively of a sole having a breast flap split therefrom and spaced from each other to provide an opening through which the flap extends when the sole engages said faces, said support for the heel-seat portion of the sole having a face to separate the flap from the sole and to deflect it into the opening, a matrix plate, an abrasive member, and means to move the supports and the matrix plate past the member thereby to cause said

member to force the flap against the matrix plate for skiving the flap at selected localities.

5. An abrading machine having, in combination, a table constructed to support a sole having a flap split therefrom and provided with a slit through which the flap extends, a matrix secured to the under-side of the table and mounted for adjustment toward and away from the slit, a rotary abrasive member, said table being mounted for movement to carry the matrix past the abrasive member thereby to force the flap against the matrix for varying the thickness of the flap at selected localities, and mechanism to operate the table.

15. 6. In a machine of the class described, a table constructed to support a sole having a flap split therefrom and provided with a slit through which the flap extends, a matrix plate secured to the under-side of the table and mounted for adjustment toward and away from the slit, a flap-reducing member, means to rotate the table to move the matrix plate in an orbital path past the reducing member thereby to force the flap extending through the slit against said plate for shaping the flap to a form determined by the plate, an abutment mounted for pivotal movement to facilitate the adjusting of the matrix plate relatively to the slit, and an indicator extending above the table and connected to said abutment constructed and arranged to permit the operator to set the abutment in a predetermined position.

7. An abrading machine having, in combination, a member constructed and arranged to be positioned between the shank portion of a sole and a heel-breast covering flap split therefrom, a matrix plate adjustably secured to the member, an abutment for positioning the matrix plate relatively to said member, means for enabling the operator accurately to adjust the abutment relatively to the member, abrasive means, and mechanism to move the member and the matrix plate past the abrasive means for forcing the flap against the matrix plate thereby to reduce the flap at selected localities.

8. An abrading machine having, in combination, a member constructed and arranged to be positioned between a sole and a heel-breast covering flap split therefrom, a matrix plate adjustably secured to said member, abrading means, and means to cause relative movement between said member and said means to force the flap against the matrix plate thereby to reduce the flap at selected localities.

55. 9. An abrading machine having, in combination, a member constructed and arranged to support a sole having a flap split therefrom and provided with a slit through which the flap extends, a matrix plate secured to the member and mounted for adjustment toward and away from the slit, abrasive means, and means to move the member and the matrix plate in an orbital path past the abrasive means thereby to force portions of the flap extending through the slit against the matrix plate to reduce the flap to a shape determined by the plate.

70. 10. In an abrading machine, a support and a matrix plate constructed and arranged to be positioned between a sole and a heel-breast covering flap split therefrom, a rotary abrasive member, and means to effect relative movement of the member on one hand and the matrix plate and the support on the other hand to reduce the flap at selected localities in accordance with the shape of the matrix plate, said

matrix plate being adjustable relatively to the support in accordance with the portion of the flap it is desired to reduce.

11. In an abrading machine, a support and a matrix plate constructed and arranged to be positioned between a sole and a heel-breast covering flap split therefrom, an abrasive belt, and means to move the support and the matrix plate past the belt to skive the flap at selected localities in accordance with the shape of the matrix plate said matrix plate being adjustable relatively to the support in accordance with the portion of the flap it is desired to reduce.

15. 12. An abrading machine having, in combination, a support provided with a slit, a matrix plate, means to clamp the support and the matrix plate together, said support and said matrix plate being mounted for relative adjustment to vary the distance between the plate and the slit, an abrasive member, and means to move the support and the matrix plate past the abrasive member in a plane disposed at substantially right angles to the plane of the path of rotation of said abrasive member.

20. 13. An abrading machine having, in combination, a support for a sole having a heel-breast covering flap split therefrom, said support being provided with an opening to receive the flap, a matrix plate, members movable to centralize the sole upon the support, an abrasive member, and means to move the support and the matrix plate past the abrasive member thereby to force the flap against the plate for varying the thickness of the flap at selected localities.

25. 14. An abrading machine having, in combination, a table constructed to support a sole having a heel-breast covering flap split therefrom and provided with an opening to receive the flap, a matrix plate secured to the under-side of the table, a rotary abrasive member, said table and said matrix plate being mounted for movement in an orbital path to cause the abrasive member to force the flap against the matrix plate thereby to vary the thickness of the flap at selected localities, and means for adjusting the abrasive member toward and away from the table to vary the minimum thickness to which the flap is reduced.

30. 15. An abrading machine having, in combination, a member constructed to support a sole having a heel-breast covering flap split therefrom and provided with an opening through which the flap extends, a matrix plate secured to the member, abrasive means movable in a closed path, a flap-guiding member to move the flap toward the matrix plate, and means for moving the sole-supporting member past the flap-guiding member to cause the flap to be positioned adjacent to the matrix plate and then past the abrasive means for forcing the flap against said plate to vary the thickness of the flap at selected localities.

35. 16. An abrading machine having, in combination, a member constructed to support a sole having a heel-breast covering flap split therefrom and provided with a slit through which the flap extends, a matrix plate carried by the member and mounted for adjustment toward and away from the slit, abrasive means, means to move the member and the matrix plate in an orbital path past the abrasive means thereby to force portions of the flap extending through the slit against the matrix plate to reduce the flap to a shape determined by said plate, and means comprising an indicator to enable the operator

to determine at a glance the position of the matrix plate relatively to the slit.

17. An abrading machine having, in combination, a member constructed and arranged to support a sole having a heel-breast covering flap split therefrom and provided with a slit through which the flap extends, a matrix plate secured to the member and mounted for adjustment toward and away from the slit, a separator plate defining one side of the slit and constructed and arranged to deflect the flap through the slit as the flap is moved along the member against the separator plate, abrasive means, and means for moving the member and the matrix plate in an orbital path past the abrasive member to force portions of the flap extending through the slit against the matrix plate thereby to reduce the flap to a shape determined by said plate.
18. A machine of the class described having, in combination, a table constructed to support a sole having a heel-breast covering flap split therefrom and provided with an opening through which the flap extends, a matrix plate secured to the table and mounted for adjustment toward and away from the opening, a separator plate which defines a portion of one end of said opening, said separator plate being constructed and arranged to cause the flap to be moved through the opening and to cause the heel-seat portion of the sole to override the separator as the sole is forced against the same, a flap-reducing member, and means for moving the table and the matrix plate in an orbital path past the flap-reducing member to force portions of the flap extending through the opening against the matrix plate thereby to reduce the flap to a shape determined by the matrix plate.

19. An abrading machine having, in combination, a drum mounted for rotation and provided with an opening shaped to receive a heel-breast covering flap of a sole supported by the drum, a matrix plate secured to the drum and mounted for adjustment toward and away from the opening, a separator plate provided with a face which extends beyond the surface of the drum, said separator plate being constructed and arranged to deflect the flap through the opening and to cause the heel-seat portion of the sole to override the separator plate as the sole is forced against the same, an abrasive member, and means for rotating the drum to move the matrix plate in an orbital path past the abrasive member for forcing portions of the flap extending through the opening against the matrix plate thereby to reduce the flap at selected localities.

20. A machine of the class described having, in combination, a support for a sole having a heel-breast covering flap split therefrom, said support being provided with an opening shaped to receive the flap, a portion of the support defining one side of the opening being constructed and arranged to separate the flap from the sole and to guide the flap through the opening as the sole is slid along the support, a flap-reducing member, a matrix plate, and means for causing relative movement of the flap-reducing member on one hand and the support and the matrix plate on the other hand to skive at selected localities portions of the flap extending through the opening.

21. An abrading machine having, in combination, supports provided with faces constructed and arranged to engage the heel-seat and the shank portions, respectively, of a sole having a heel-breast covering flap split therefrom and spaced

from each other to form an opening, said support for the heel-seat portion terminating in an undercut face which defines one side of the opening and serves to separate the flap from the sole and to deflect it into the opening when the sole is forced against said support, a matrix plate secured to one of the supports, an abrasive member, and means to move the supports and the matrix plate past the abrasive member for causing the member to force the flap against the matrix and thereby to reduce the thickness of the flap at selected localities.

22. An abrading machine having, in combination, supports provided with faces constructed and arranged to engage the heel-seat and shank portions, respectively, of a sole having a heel-breast covering flap split therefrom and spaced from each other to form an opening, the support for the heel-seat portion of the sole having a face which extends beyond the sole-engaging face of the other support and serves to separate the flap from the sole and to deflect it into the opening when the sole is forced against said support, a matrix plate secured to the support for the shank portion of the sole, an abrasive member, means to move the supports and the matrix plate past the abrasive member for causing the member to force the flap against the matrix and thereby to reduce the thickness of the flap at selected localities, and means to adjust one of the two supports relatively to the other for varying the width of the flap-receiving opening.

23. An abrading machine having, in combination, a turret provided with a plurality of units each of which comprises a matrix plate and a pair of supports constructed and arranged to engage the shank and heel-seat portions, respectively, of a sole having a heel-breast covering flap split therefrom, said supports being spaced from each other to provide an opening for receiving the flap, an abrasive member, and means for rotating the turret successively to move the units past the abrasive member thereby to cause the flaps positioned in the units to be forced against the respective matrices for reducing the flaps at selected localities.

24. An abrading machine having, in combination, a turret provided with a plurality of units each of which comprises a matrix plate and a pair of supports constructed and arranged to engage the shank and heel-seat portions, respectively, of a sole having a heel-breast covering flap split therefrom, the supports of each unit being spaced from each other to provide an opening shaped to receive the flap and mounted for relative adjustment to vary the width of the opening, an abrasive member, and means for rotating the turret successively to move the units past the abrasive member to reduce the flaps of the soles carried by the units at selected localities.

25. An abrading machine having, in combination, an endless abrasive belt, a turret mounted for rotation and provided with a plurality of units each of which comprises a support and a matrix plate constructed and arranged to be positioned between the shank portion of a sole and a heel-breast covering flap split therefrom, a support constructed and arranged to engage the heel-seat portion of the sole and spaced from the first-named support to provide an opening for receiving the flap, and means to rotate the turret in a plane disposed substantially at right angles to the plane of the path of rotation of the belt thereby successively to move the

units past the belt for reducing the flaps at selected localities.

26. An abrading machine having, in combination, a rotary drum provided with a plurality of units each of which comprises supports constructed and arranged to engage the shank and heel-seat portions, respectively, of a sole having a heel-breast covering flap split therefrom and spaced to provide an opening for receiving the flap, a matrix plate secured to the inside of the drum, an abrasive member positioned inside the drum, and means to rotate the drum to cause the abrasive member successively to force the flaps extending through the opening of the units against the respective matrices of the units thereby to skive the flaps at selected localities.

27. An abrading machine having, in combination, a rotary drum provided with a plurality of units each of which comprises supports which are constructed and arranged to engage the shank and heel-seat portions, respectively, of a sole having a flap split therefrom and are spaced to provide an opening through which the flap

extends, a matrix secured to the inside of the drum, and gages within the opening to position the sole widthwise upon the supports, an abrasive belt, a guide positioned adjacent to the inside of the drum for bending the portion of the flap extending through the opening toward the matrix as the drum is rotated, and means to rotate the drum for causing the abrasive belt to force the flap extending through the opening against the matrix thereby to skive the same to a shape determined by the matrix.

28. In an abrading machine, a support and a matrix plate constructed and arranged to be positioned between a sole and a heel-breast covering flap split therefrom, a rotary abrasive member, and means to move the support and the matrix plate past the member in a path tangent to said member to reduce the flap at selected localities in accordance with the shape of the matrix plate, said matrix plate being adjustable relatively to the support.
